UNITED STATES PATENT OFFICE.

GEORGE W. WILSON, OF HARTFORD, CONNECTICUT.

BUCKLE.

SPECIFICATION forming part of Letters Patent No. 319,769, dated June 9, 1885.

Application filed March 18, 1884. (No model.)

To all whom it may concern:

Be it known that I, GEORGE W. WILSON, of Hartford, in the county of Hartford and State of Connecticut, have invented certain new and 5 useful Improvements in Buckles; and I do hereby declare that the following is a full, clear, and exact description of the invention, whereby a person skilled in the art can make and use the same, reference being had to the accompanying drawings, and to the letters of reference marked thereon.

Like letters in the figures indicate the same parts.

Figure 1 is a plan view of a frame-blank as 15 cut from sheet metal. Fig. 2 is a bottom view of a buckle after the edges of the blank have been folded over to form the frame. Fig. 3 is a view in cross-section of the frame on plane denoted by line xx of Fig. 2. Fig. 4 is a view 20 in cross section of the buckle on plane denoted by line yy of Fig. 2. Fig. 5 is a bottom view of a buckle as fastened to a strip of cloth. Fig. 6 is a top view of same. Fig. 7 is a view 25 in cross-section on plane denoted by line xx of Fig. 5.

My improvement relates more particularly to the class of buckles in common use on pants, but is applicable to all other classes of buckles.

It consists in the frame struck from a single 30 piece of metal, when combined with the pivoted tongue borne in said frame, and in the improved fastening device integral with or attached to a buckle-frame.

In the accompanying drawings, the letter a 35 denotes a frame-blank, cut from a sheet of any suitable material—as sheet-brass; b , the

tongue-space; b' , a fastening device consisting of sharp-pointed prongs $c c'$, formed from the metal when the blank is cut out, as by means of dies in the ordinary manner.

40

The edges of the blank a are folded over to form the frame a' of the buckle, and the ends of the tongue-shaft d are grasped between the folded edges upon each side, between which are formed the sockets a^2 , and in which sockets 45 the shaft turns freely.

In order to fasten this device to any object—as a piece of cloth, e —the prongs are set at about right angles to the plane of the buckle and are thrust through the material and 50 through the openings f in the plate g . This plate has a central opening or socket, h , into which the pointed ends of the prongs are thrust, in order to more securely hold them and to prevent them from catching into objects which may come in contact with the plate. 55

I claim as my invention—

1. In combination, the metallic buckle-frame a' , folded back upon itself on all sides, with the tongue-sockets a^2 in the opposite sides 60 of the frame, and a tongue-shaft, d , pivotally supported in the tongue-sockets, the frame bearing the integral sharp-pointed fasteners c c' , all substantially as described.

2. The frame-blank a , made from a metallic 65 plate with the corners cut away, and having a tongue-space, b , and the integral fastening-prongs $c c'$, all substantially as described.

GEORGE W. WILSON.
